UNITED STATES PATENT OFFICE.

JAMES BOWEY AND GEORGE ROCKLIFFE, OF SUNDERLAND, ENGLAND.

SPOOL-HOLDER FOR SEWING-MACHINES.

SPECIFICATION forming part of Letters Patent No. 700,167, dated May 20, 1902.

Application filed June 13, 1899. Serial No. 720,426. (No model.)

To all whom it may concern:

Be it known that we, JAMES BOWEY and GEORGE ROCKLIFFE, subjects of the Queen of Great Britain and Ireland, and residents 5 of Sunderland, in the county of Durham, England, have invented a certain new and useful Device for Preventing the Entanglement and Breakage of Thread at the Bobbin-Holders of Sewing-Machines, (for which we have applied for patents in Great Britain under No. 10 24,026, dated November 15, 1898, and in Germany under Kaffenbuch No. 1,519, dated April 12, 1899,) of which the following is a specification.

15 This invention relates to a device for preventing the entanglement and breakage of thread at the bobbin-holders of sewing-machines.

Under certain conditions when the thread 20 is unwinding the natural tendency of the coils on the bobbin is to become slack, and according to the prevalent practice of mounting the bobbin it frequently happens that these loose coils slip over the end of the bobbin, whereupon they get entangled around the bobbin-holder or supporting-spindle fitted upon the machine-arm, and eventually the thread is broken, with the accompanying inconvenience. 25 To obviate the aforementioned liability, it has been proposed to fix the bobbin to a disk fitted to revolve around the bobbin-holder or supporting-spindle and made of such a size as to receive and retain any coils detached from the bobbin. However, to procure 30 effectiveness this arrangement necessitates the disk being made considerably larger in diameter than the bobbin, whereby clumsiness and incompactness at once arise and render its use impracticable.

40 The object of our invention is to avoid the defects of the said arrangement; and to this end we fix the bobbin to a disk adapted to be revolvable around the bobbin-holder or supporting-spindle and bear upon another disk 45 that is secured to the holder or spindle and furnished with a shield or guard, the arrangement being such that the necessity for a device of undue dimensions is obviated, while any coils detached from the bobbin are received and retained by the combined disks,

whereby they are effectually hindered from fouling and breaking.

We will fully describe our invention with the aid of the accompanying drawings, wherein—

55 Figure 1 is a general elevation representing our device with the parts assembled ready for use. Fig. 2 is a central vertical section of same with the bobbin displaced. Figs. 3 and 4 are plans of details.

60 A is a disk of any suitable material, brass or aluminium by preference, for receiving and holding the bobbin B centrally and so that it may revolve therewith. The surface of this disk may be dished or recessed, flat 65 or corrugated, and it is perforated centrally to permit the passage of the ordinary bobbin-holder or spindle C, around which it revolves as the thread is unwound from the bobbin B during the operation of the machine, the perforation being somewhat larger in diameter 70 than the part C to insure unimpeded rotation. For effecting the requisite connection between the disk A and bobbin B we furnish the former with a split tube D, coincident 75 with the central hole therein and having an internal diameter slightly greater than the part C and being of an external size to fit tightly into the usual hole traversing the length of the bobbin. To assist this connection, we may slit a portion of the tube D to render it resilient, as shown at E E, Figs. 2 and 4, or we may provide pins F F on the disk A, as illustrated in Fig. 2, for penetrating the bobbin end. We find the tube D to 80 be quite efficient alone, and we prefer to adopt it, though, as will be obvious, we may use the pins F F as the only means of fixture.

85 G is a ring or washer, of felt, rubber, or other soft material, intervening and tightly 90 pressed between the bobbin B and disk A to prevent the thread catching under the bobbin. We recommend its employment; but it is not absolutely necessary, as the purpose served by it and just explained will usually 95 be met by pressing the bobbin tightly against the disk.

H indicates the arm of the machine, between which and the disk A another disk J is interposed. This disk J, as will be clearly seen 100

from Fig. 2, is formed with a recess wherein the disk A is located, so as to be freely revoluble on unwinding the thread from the bobbin B, while the disk J remains stationary upon the holder C and the arm H. To procure this fixture of the disk J, it is united to the holder C in much the same fashion as that already described in joining the disk A to the bobbin B, a split tube K being provided centrally upon the disk J, wherein, to coincide with the tube, a hole is made through which the holder C passes to be gripped by the upper part of the tube K. On the disk J we form or fix a guard or shield L for partially inclosing and extending above or toward the top of the bobbin, thereby effectually preventing any loose coils forming at the upper part of said bobbin from falling outside of the disks A and J. Figs. 3 and 4, respectively, show the disks J and A (that are combined in use, as above explained) apart. As will be evident, by this disposition the diameter of the disk A need not exceed and the diameter of the disk J need only slightly exceed that of the bobbin B, so that a ledge M is obtained. Hence compactness and neatness result. Thus it will be seen that the disk A and bobbin B revolve together, and as the thread is unwound any coils becoming slack and falling fall upon the ledge M, whereon they are retained clear of the spindle or holder C, while they are also prevented from getting underneath the bobbin by the washer G. Consequently entanglement and breakage

are avoided simply and effectually by a device that may be produced at a small cost and takes up little room in use.

What we claim as our invention, and desire to secure by Letters Patent, is—

In combination with an arm of a sewing-machine and the spindle thereon to receive a bobbin, a recessed disk carried by the arm around said spindle and retained stationary by the engagement of a gripping device carried by it with the spindle, a rotatable disk of slightly larger diameter than the bobbin end and located in the recess in the stationary disk, said rotatable disk being provided with a split tube whereby the bobbin is attached to it, a disk or washer between the bobbin and the rotatable disk and adapted to form a ledge covering the space between the rotatable disk and the fixed disk on which loose coils of thread are received, and a shield or guard carried by the stationary disk and arranged so as to partially surround the rotatable disk and the bobbin for preventing any loose coils forming at the upper part of the bobbin from falling outside of the disks, substantially as described.

In witness whereof we have hereunto set our hands in the presence of two witnesses.

JAMES BOWEY.

GEORGE ROCKLiffe.
